UNITED STATES PATENT OFFICE.

MARY E. ROARKE, OF NEW YORK, N. Y.

GARMENT-WEIGHT.

1,102,438.

Specification of Letters Patent. Patented July 7, 1914.

Application filed April 10, 1913. Serial No. 760,201.

To all whom it may concern:

Be it known that I, MARY E. ROARKE, citizen of the United States, residing at New York, in the county of New York and State of New York, have invented certain new and useful Improvements in Garment-Weights; and I do declare the following to be a full, clear, and exact description of the invention, such as will enable others skilled in the art to which it appertains to make and use the same.

This invention relates to garment weights, and more especially to those manufactured in tape form of variable lengths and widths.

The primary object of the invention is in the provision of an article of manufacture of the class described which is composed of pliable material or fabric which is susceptible of a slight elasticity to which is secured a plurality of closely assembled weights, the latter however being slightly separated and the flexible material entirely inclosing and overlapping the weights thus assembled, whereby a smooth and uninterrupted surface is presented on both sides of the tape.

Another object of the invention consists in a garment weight constructed in such a manner that the same will always retain its original formation, however permitting the free uninterrupted movement and flexibility of a garment to which the same is attached.

With these and other objects in view, the invention consists of certain novel features of construction, combination and arrangement of parts as will be more fully described and claimed.

Figure 1 is a plan view of the invention with a portion of the cover removed therefrom to show the interior construction of the same; Fig. 2 is a longitudinal section taken on the line 2-2 of Fig. 1; Fig. 3 is also a front elevation of the invention showing a slight modification of the invention wherein a single row of weights are employed with a part of the cover broken away; Fig. 4 is a further modification showing a longer tape to that shown in Fig. 1 but similarly constructed; Fig. 5 is a side elevation of the weight which is employed in carrying out the invention; Fig. 6 is a plan view of the same; Fig. 7 is an end view of the weight; Fig. 8 is a longitudinal section of a weight showing a modification of the invention in this respect.

In the illustrative embodiment of the invention 1 represents a sheet of textile fabric

preferably of canvas but it must necessarily be thoroughly pliable and slightly elastic. To the strip of flexible material 1 is secured a shorter strip 2 which is held in position 60 when the weights 3 are secured in position as hereinafter described.

The weights 3 are especially designed for the purpose and are concavo-convex in cross section or cup shaped as clearly shown. The 65 weights are provided with openings 5 which are in alinement and centrally disposed through which a thread is passed and through the textile fabric, whereby said weights are held in their proper position in 70 respect to one another and further securing the fabrics 1 and 2 together.

As clearly shown the corners of the weights 3 are slightly rounded and while the edges of said weights are separated, 75 they are closely assembled in order that the material which covers the same will not become creased or lose its original formation during the usual wear after the tape has been properly secured to a garment, said tape 80 compensating for the variable positions of the body, the weights thus assembled and secured to the flexible material causing the same to always assume its original or normal position. Surrounding the weights 3 85 thus attached to the fabric is secured felt 6 or other pliable material of a like nature which compensates substantially for the thickness of the weights whereby the outer edges of the outer row of weights are covered and protected, and when the sheets of the textile fabric 2 and 3 are secured by sewing or stitching in a manner shown in Fig. 2, the edges of the tape thus constructed will 90 be soft and pliable and no discomfort whatever will be experienced by the wearer when the garment is in use.

In Fig. 8 a slight modification of the invention is shown wherein the edges of the weight are covered by tape or flexible material 3' so that should the edges of the weights come together during the movement of the garment the tape will be rendered more pliable. The garment weight as herein shown and described can be manufactured by machinery at a small cost and produced in perfect and complete form for ready and convenient attachment to a dress or other garment.

It is to be understood that any number of 110 weights may be assembled side by side in order to provide a sufficient weight and

that the tapes may be of suitable length; all of which is apparent.

The extended tabs 7 which form opposite ends of the tape provide efficient means for 5 sewing or otherwise securing the tape to the garment. However it is evident that said tape may be sewed along the entire longitudinal edges thereof or the same secured at intervals along its length.

10 Heretofore many attempts have been made to devise or invent a reliable and practical article of this character but the same possessed many disadvantages which is obvious from the fact that units or weights 15 are employed which are separated from each other and circular in form, whereby in a short length of time the material of which the garment is composed would show creases and expose the formation of the weights 20 thus employed along the length of the tape. Again such weights are separated but secured together by a strip or string whereby in time the weights will become loosened and more closely assembled and therefore the 25 full intents and purposes of the invention are destroyed. These objections cannot possibly occur in the construction herein shown and described, as it is obvious that by the employment of the closely assembled rectangular shaped units or weights and providing sufficient space between the same to 30 permit the necessary movement of the garment, the results previously referred to are accomplished.

35 If found desirable the fabrics 2 and 3 may be overlapped at their edges and stitched or otherwise secured whereby a smooth edge is presented, and it is further to be noted that a single tape may be provided with a variable number of weights 40 as may be required.

In conclusion it is evident that the weights thus constructed cannot possibly mark, wear or cut the lining or garment as the friction of the weights is reduced to a minimum. 45

From the foregoing description taken in connection with the accompanying drawings, the construction and operation of the invention will be readily understood without requiring a more extended explanation. 50

Various changes in the form, proportion and the minor details of construction may be resorted to without departing from the principle or sacrificing any of the advantages of the claimed invention. 55

What is claimed is:

1. A garment weight comprising a tape having a pocket secured thereto, a series of weights secured within the pocket thus constructed and provided with openings whereby they may be secured within the pocket adjacent to one another, and a cushioning material arranged in said pocket around the edges of the series of weights. 60

2. A garment weight comprising a tape 65 composed of a strip of material, a pocket secured to the same but shorter than said material, said pocket having overlapping edges which are secured together, a strip of pliable material located within the pocket 70 adjacent to the edges thereof whereby a space is formed, rectangular shaped weights secured within the space formed by said pliable material, and means for securing the weights to the pocket and textile material. 75

In testimony whereof I have hereunto set my hand in presence of two subscribing witnesses.

MARY E. ROARKE.
